PROTHROMBIN TIME DETERMINING UNIT

Robert H. McKim, Palo Alto, Calif., assignor to Oxford
Laboratories, San Mateo, Calif., a corporation of
California

Filed Mar. 25, 1963, Ser. No. 74,115

Term of patent 14 years

(Cl. D16—2)

FIG. 1

FIG. 2

FIG. 3

FIGURE 1 is a front elevation of a prothrombin time determining unit, showing my new design;

FIGURE 2 is a side elevation thereof taken from the right of FIGURE 1; and

FIGURE 3 is a perspective view thereof, taken at a reduced scale with the elements shown in broken lines for illustrative purposes only.

I claim:

The ornamental design for a prothrombin time determining unit, as shown and described.
